UNITED STATES PATENT OFFICE.

JOHN N. FOWLER, OF NEW YORK, N. Y.

IMPROVEMENT IN ROCKING APPARATUS.

Specification forming part of Letters Patent No. 121,094, dated November 21, 1871.

To all whom it may concern:

Be it known that I, JOHN N. FOWLER, of the city, county, and State of New York, have invented a certain Improved Machine for Recreation by Children and others, which may be termed a Rocking-Swing, of which the following is a specification:

The swing may be used by two persons at a time or by only one. When it is used by two the two may be of equal or of wide-differing weights. It is capable of being folded in a small compass for storing or transportation.

The following is a detailed description of what I consider the best means of carrying out the invention.

The accompanying drawing forms a part of this specification.

Figure 1 is a side elevation, with the parts folded together. Fig. 2 is a central longitudinal section. Fig. 3 is a plan view. The last two figures show the parts extended for use.

Similar letters of reference indicate like parts in all the figures.

A is a rigid frame-work, serving as a stand or support for the rocking part. Certain parts are marked A^1 , A^2 , &c., to distinguish them. The principal frames marked A are two pieces of wood or other suitable material mounted in parallel positions, each presenting a regularly-curved or arched form. They are connected by firm cross-bars A^1 A^2 , and these latter are connected by a longitudinal piece, A^3 , which extends lengthwise of the frame-work, and forms an adjustable attachment for certain springs, which will be described further on. The bases of the arched pieces A A rest at one end directly upon the floor or ground. At the other end they rest on movable arms A^4 , which are capable of being turned around on vertical pivots a , shown in dotted lines. These arms A^4 may be turned inward, as shown in Fig. 1, to facilitate transportation. The machine may be used with the arms in this position under ordinary circumstances, but when in consequence of a superior weight on that end of the rocking portion, or in consequence of the violent rocking of a vigorous child, there is danger of the entire machine tilting over the arms or movable base pieces A^4 should be extended by turning them on the pivots a , as centers, and be caused to stand in the position shown in Fig. 2. B represents the rocker-frame. Some parts are marked

B^1 , &c., to distinguish them. The principal part is composed of two parallel rockers or inverted arches, B B, mounted and adapted to roll upon the arches A. They are connected by stout cross-pieces B^1 B^2 . A peculiarly-formed yoke piece, B^3 , is firmly bolted at each end to the cross-pieces B^1 B^2 and extends around under the cross-pieces A^1 A^2 and the central longitudinal piece A^3 and their several attachments, as represented. C^1 C^2 are grooved pulleys mounted in spring brackets D^1 D^2 , which latter are mortised into the cross-pieces A^1 A^2 and rest on coiled or other springs in the bottom of said mortises so that the brackets and the attached pulleys are capable of yielding by the elastic action of the springs. The grooves in the pulleys C^1 C^2 match to the inner face of the curved portions of the yoke B^3 . As the rocker B and its attachments move in alternately opposite directions the yoke B^3 plays up and down each side and turned the grooved pulleys C^1 C^2 . The lower portion of the yoke B^3 strikes against an adjustable spring, E, which is made by preference of several thin plates or leaves like a portion of a carriage-spring, but the material should be thin, so as to yield with moderate force. This spring is curved, as represented, and is confined adjustably by a screw, e, and nut e^1 , which may be operated by hand or any suitable wrench or the like. The screw or bolt e is provided with a large washer, e^2 , under its head, and is capable of being adjusted backward and forward in a slot in the piece A^3 , as will be obvious. When the nut e^1 is slackened the screw-bolt e may be changed backward and forward in the slots, and the spring E may be changed backward and forward relatively to it. This latter movement is effected by means of a long slot in each several leaf of the spring E. The construction allows the spring E to be adjusted both in its force and in its position so that when the rocker-frame B and its attachments rock in one direction, so as to make the seat M^2 the lowest, the force of the spring E will be felt to arrest its further motion in that direction, and will be felt earlier or later, or more powerfully or less powerfully, according to the adjustment. This matter of the adjustment of this spring is very important in practice, and may be facilitated by the employment of various devices not necessary to represent, such as graduations marked properly on the frame to indicate the adjustment for chil-

children of different weights or ages. It will be understood by mechanics that when the nut e^1 is unscrewed the shifting of the spring E to the left in Fig. 1 will make it press upon the yoke B³ earlier, and that the shifting in the opposite direction will make it commence to act later. It will be also understood that by shifting the entire bolt e and its connected spring to the left in the slot, the other adjustment or length of the spring being the same, the leverage of the spring or the effect of its action on the yoke B³, and consequently its effect on the entire rocking parts will be increased, while by shifting these parts to the right the effect will be diminished. It is thus easy to secure a proper adjustment for any load. G is another spring, which may be also made of several leaves, if preferred, but its duties are less important. It is mounted on the upper side of the longitudinal central bar A³, and arrests the motion of the rocking parts in the opposite direction. The function of this spring G is purely to arrest the motion gently and throw it back with a lively motion in the opposite direction. I may add that the same effect is also induced by the other spring E, in addition to its function of adjustably balancing any inequality in the loads on the opposite ends of the rocking part B. M¹ M² are folding-seats hinged to the respective ends of the rocking parts B, and adapted each to accommodate a child or grown person, according to the size of the machine. When the weight in the seats M¹ and M² are about equal the bolt e should be shifted as far to the left as possible and the spring E held thereby should be shifted along to the right. The result will be a short and stiff spring E, but only commencing to act at a very late period in the descent of the seat M². Under these conditions the action of the spring E underneath will be very similar to the action of the spring G above. Each will only exert its force at the very last part of the rocking motion in the one direction or the other, and will simply soften the shock at the end of the motion and throw the rocking part actively in the opposite direction. When one person is much heavier than the other the heavier must always take the seat M².

I will suppose, for an extreme case, that a child or other person is to rock alone. Place him in the seat M² and that end of the rocking part B and its attachments will be depressed. Now, the spring E and its adjustable attachment e must be shifted so as to give the spring E a long action and cause it to commence its action early. These changes are effected by shifting the bolt e to the right and drawing the spring E to the left. When the proper point is attained the seats M¹ M² will stand about even or level with each other when the machine is at rest, the force of the spring E balancing or nearly balancing the excess of weight in the seat M². Now, thus adjusted, the rocker B and its connections may be operated about the same as if the two ends were evenly loaded. The force of the spring E will bear during a good part of each vibration with such

force on the yoke B³ as to about equalize the action. It will be understood that there may be adjustable footboards to accommodate children or persons of different sizes, and that any suitable fastening means may be provided for insuring the safety of the children in the exciting and highly pleasurable use of the machine. The bottom of the fixed part A and turnable arms A⁴ may be shod with rough leather, felt, or the like to prevent its slipping on a carpet. The yoke B³, in addition to its functions of guiding the rocker B and its attachments so as to keep the parts properly in place upon the stand A A, and of receiving the action of the adjustable spring E, and balancing the over-loaded end of the rocker, also serves to connect the entire rocker and stand together in transporting or removing the machine about. If a domestic or other attendant lifts the machine by the rocker B the entire frame A necessarily is lifted with it by the action of the curved portions of the yoke B³ against the slightly elastically-mounted pulleys C¹ C², as will be obvious on inspection. I propose in some cases to provide a grooved roller on the end of the spring E to reduce the friction on the yoke B³. I also propose in high-priced machines to employ a screw to urge the spring E to the right or left, so that its position and force may be adjusted with more facility and greater delicacy. I propose, also, in some cases to have the top of the stand A flat instead of arched, the yoke B³ being correspondingly modified. So long as the yoke B³ is curved exactly with the proper curvature to correspond with the motion there will be no function performed by the spring behind the brackets D¹ D², except deadening the sound of the pulleys C¹ C². But if, as may often be the case after the construction has been some time in use, the curvature does not agree exactly with the motion then the yielding of those springs allows for the slight discrepancy. I propose in some cases to make the spring-brackets D¹ D² longer, and to mount in each two grooved pulleys, one inside of the yoke, as here shown, and the other outside. The latter will bear against the curved exterior of the yoke B³ and aid to keep the parts working truly and smoothly; but I do not consider them necessary in ordinary cheap forms of the construction.

Any part not here described or shown, it will be understood, may be made in any ordinary or suitable manner. This may include cushions, fastenings for children, and all kindred devices.

I claim as my invention—

1. The folding-seats M¹ M² on the rocker B, in combination with the stand A, and arranged to operate thereon, as and for the purposes specified.
2. The yoke-piece B³, formed and arranged as represented, to act on guide-pulleys C¹ C², and to serve relatively to the rocker B and seats M¹ M², as and for the purposes specified.
3. The spring E and adjustable fastening e, arranged and adapted to operate relatively to the rocker B and seats M¹ M², working on the stand A, as specified.

4. The extensible base pieces A^4 A^4 on the rocker-stand A, arranged to serve as represented relatively to the rocker B and seats M^1 M^2 , for the purposes specified.

5. The entire combination of the rocker B with its folding-seats M^1 M^2 , and yoke B^3 with the stand A, extensible feet A^4 , guide-pulleys C^1 C^2 , and springs E G, as specified.

In testimony whereof I have hereunto set my name in presence of two subscribing witnesses.

J. N. FOWLER.
